VALVE-OPERATING MECHANISM.

Application filed October 3, 1923. Serial No. 666,319.

This invention relates to regulating apparatus for coke ovens of the by-product type, and more particularly to apparatus for simultaneously regulating the ascension pipe cap and damper valve of such ovens.

One object of the present invention is to prevent the creation of undue pressure within the coke ovens, due to the oven being closed off from the collecting main and from 10 the atmosphere at the same time, as is the case when the ascension pipe cap and damper valve are operated independently.

Another object is the provision of a suitable power operating mechanism for simultaneously operating the ascension pipe cap and damper valve, which means may be controlled from a point remote from the ovens.

Another object is the provision of a novel form of fluid pressure operated mechanism 20 for operating the ascension pipe cap and damper valve of a coke oven of the type described, and also to provide a source of fluid pressure adapted to be moved from oven to oven, and to be operatively connected to the 25 operating apparatus.

A further object is to provide an apparatus for simultaneously operating the ascension pipe cap and damper valve of by-product coke ovens, such apparatus being composed of the novel combination and construction of parts illustrated in the accompanying drawings, and described in the following specification.

In the drawings, Figure 1 is a diagrammatic plan of a plurality of coke ovens and pusher machine with this invention applied thereto.

Figure 2 is a similar end elevation.

Figure 3 is an elevation showing the ascension pipe cap and damper valve operating mechanism on a large scale.

Figure 4 is a sectional side elevation of the coupling mechanism for forming a connection between the source of fluid pressure 45 on the pusher machine and the operating mechanism.

Figure 5 is a fragmentary sectional elevation of the forward end of the coupling mechanism, showing it in operative connection with the receiving cone or head.

Figure 6 is a front elevation of the coupling mechanism.

Figure 7 is a plan view, similar to Figure 1, showing the use of two coupling plungers, 55 which are necessary in the event of the dis-

tance on the pusher machine between the center line of the door extracting ram and the center of the leveling bar being an even multiple of the distance between centers of the ovens.

Referring more particularly to the drawings, the numeral 2 designates the battery of ovens as a whole, of which only a portion is shown, the ovens shown being numbered from 3 to 8, respectively. Each oven 65 is fitted at one end with an ascension pipe 9 and the top or upper end of each pipe 9 is provided with a hinged cover or cap 10, whereby the oven chamber is opened or closed to the atmosphere by raising or closing down the ascension pipe cap.

A suitable collecting main 11 extends longitudinally of the ovens and is connected to each oven through damper valve boxes or casings 12 mounted on the main 11 and connected to the ascension pipes 9 by lateral extensions 14. A damper valve disk 15 is mounted within each of the valve boxes 12 and is adapted to be moved vertically relative to the valve seat 16 so as to open and 80 close the passage from the oven chamber to the collecting main 11.

A pusher machine 17 travels on tracks 18 extending along the side of the battery of ovens 2, and carries the usual door extractor 19, pusher ram 20, and leveler bar 21 and their accompanying mechanism, these parts being indicated by their center lines only for the sake of clearness.

All of the above described oven and pusher machine construction is of standard and well known construction and it is not thought necessary to describe or illustrate it in further detail.

Heretofore, the ascension pipe caps 10 and 95 damper valves 15 have been independently and manually operated.

The practice has, heretofore, been to close the oven to the main 11 by lowering the valve 15 and then to raise the ascension pipe cap 100 10 when opening the oven to the atmosphere, and to close the ascension pipe cap 10 and then open the valve 15 when putting the oven back on the main, this practice being necessary to prevent the flow of gas from 105 the main into the atmosphere. It will, therefore, be readily seen that at each operation of these two members there was always a period when the oven was closed to both the main and the atmosphere, thus creating un- 110

due pressure within the ovens, especially if the ascension pipe cap or damper valve should fail to open promptly due to the collection of tar or other ingredients of the gas 5 on their seats.

The present invention provides for a simultaneous mechanical operation of the cap 10 and valve 15 and therefore, a fluid pressure operated cylinder 24 is mounted 10 on a suitable support 25 above the valve box 12, and has its piston rod 26 provided with a suitable cross head 27 which is connected directly to the stem 29 of the valve 15 and by link 30, rocker crank 31 and link 32 to 15 the ascension pipe cap 10, so that reciprocation of the piston rod 26 of the cylinder 24 will cause a simultaneous movement of both the valve 25 and cap 10.

The pusher machine 17 is provided with 20 an air compressor 35, driven by a motor 36 and adapted to deliver air to a reservoir 37 from which it is delivered to the cylinder 24 by means of mechanism to be described.

The compressed air from the reservoir 35 25 is conducted by pipe 38 to a three way valve 39, which valve is connected by conduits 40 and 41 to opposite ends of a fluid pressure cylinder 42, and the ports of the valve 39 are so arranged that air is delivered to 30 either end of the cylinder 42 and released from the opposite end according to the position of the valve.

The cylinder 42 has its rear end supported for universal movement on a bracket 43, and 35 has its forward end supported in a self adjusted bearing consisting of a ring 45 carrying four springs 46 which are attached to the cylinder at diametrically opposite points in such a manner that the cylinder 40 may swing for a limited distance in any direction.

The cylinder 42 is provided with a hollow coupling piston 47 which is provided at its forward end with a movable section or 45 plunger 48, having an integral valve stem 49 on its inner end and a passageway 50 therethrough. The valve stem 49 carries a valve 51 adapted to normally seat against a valve seat 52 formed on the inside of the piston walls. The outer or exposed end of the plunger 48 is provided with a rubber sealing ball 53.

As air is admitted to the rear end of the cylinder 42 the piston 47 will be forced to 55 move out of the cylinder and the valve 51 will be forced against the seat 52.

A plurality of conical or funnel shaped receiving heads 55 are spaced along the battery of ovens, two being provided for each oven, and connected by suitable conduits to the opposite ends of the cylinders 24. The heads 55 are so positioned that when the door extractor 19 is in position to remove 60 the door of an oven the piston 47 will be in line with the head 55, which communicates

with the upper end of the cylinder 24 for that oven, and when the leveler bar 21 is in position to level the charge in the oven the piston 47 will be in line with the other head 55 for that oven, which communicates with 70 the lower end of the cylinder 24.

When the pusher machine or car is positioned so that the door extractor 19 is in position to remove the door of an oven, the three way valve 39 will be turned to admit 75 air from the reservoir 37 to the rear end of the cylinder 42, thus forcing the piston 47 out of the cylinder until the plunger portion 48 is seated in and forms a sealing joint within the head 55 connected with the upper 80 end of the cylinder 24 for that oven. The forcing of the piston 47 within the head 55 will cause a rearward movement of the plunger portion 48, thus opening the valve 51 and completing the air passage to the 85 cylinder 24 from the reservoir 37, permitting the compressed air to flow into the cylinder 24 and force the piston 26 downwardly; thus simultaneously closing the damper valve 15 and opening the ascension pipe cap. 90

Before the pusher machine is moved it is necessary for the piston 47 to be removed from within the head 55, and to do this the three way valve 39 is operated to direct a 95 flow of air from the reservoir into the conduit 41, which enters the forward end of the cylinder and forces the piston 47 back into the cylinder.

When the pusher machine is positioned so that the leveling bar 21 is in position 100 to level the charge of the oven, the three way valve 39 will be turned to admit air from the reservoir 37 to the rear end of the cylinder 42, thus forcing the piston 47 out of the cylinder until the plunger portion 48 105 is seated in and forms a sealing connection within the other head 55 connected with the lower end of the cylinder 24 for that oven. Thus air is admitted to the lower end of the cylinder 24 and the piston 26 is forced upwardly so as to simultaneously open the damper valve 15 and close ascension pipe cap 10. The piston 47 is then removed from the last mentioned head 55 in the same manner as described above. 115

In order to prevent movement of the pusher machine or car prior to the removal of the piston 47 from the heads 55, piston 47 is provided with a circuit interrupter in the form of a contact ring 57 adapted to make and break a circuit through contact fingers 58. Thus when the piston is extended within either of the heads 55 the circuit is open and when it is withdrawn or in retracted position the circuit is closed. The interrupted circuit is the circuit to the motor (not shown) used to move the pusher machine from place to place.

In Figure 7 we have shown an arrangement of apparatus using two cylinders 42 130

and their accompanying mechanism, both of which are connected by three way valves 39 to the compressed air reservoir 37. This construction is only necessary in the event 5 of the distance on the pusher machine between the center line of the door extractor and the center line of the leveling bar being an even multiple of the distance between centers of the ovens, since when such a condition exists the heads 55 could not be positioned so that a single cylinder would serve both heads. The same reference numerals are used to designate the several parts of this modified structure, since the 10 construction is the same, with the exception that two cylinders 42 are used instead of one.

The operation of this modified apparatus is the same as the preferred form, with the 20 exception that one cylinder will be used, when the door extractor 19 is in position, and the other cylinder will be used when the leveling bar 21 is in position.

While we have shown and described only 25 specific embodiments of our invention, it will be understood that we do not wish to be limited to such constructions, since various modifications may be made without departing from the scope of the invention as defined in the appended claims.

We claim—

1. The combination with a battery of coke ovens of the by-product type, each of said ovens having an ascension pipe through 35 which gaseous products may pass from the oven, a cap on the upper end of each of said pipes adapted to be opened and closed to open and close said pipes to the atmosphere, a gas collecting main common to the 40 ascension pipes of all of said ovens, and damper valves connecting said ascension pipes and said main and adapted to be closed when said ascension pipe caps are opened to open said ascension pipes to the atmosphere 45 and to be opened when said ascension pipe caps are closed, of a carriage movable along said ovens, individual means for simultaneously operating the ascension pipe cap and damper valve on each of said ovens, and means carried by said carriage for operating all of said first named means.

2. The combination with a battery of coke ovens, of the by-product type, each of said ovens having an ascension pipe through 55 which gaseous products may pass from the oven, a cap on the upper end of each of said pipes adapted to be opened and closed to open and close said pipes to the atmosphere, a gas collecting main common to the ascension pipes of all of said ovens, and damper valves connecting said ascension pipes and said main and adapted to be closed when said ascension pipe caps are opened to open said ascension pipes to the atmosphere and 60 to be opened when said ascension pipe caps

are closed, of a carriage movable along said ovens, individual fluid pressure operated means for operating the ascension pipe cap and damper valve on each of said ovens, and means carried by said carriage for controlling the operation of all of said fluid pressure operated means. 70

3. The combination with a coke oven of the by-product type, having an ascension pipe through which the gaseous products 75 may pass from the oven, a cap on the upper end of said pipe adapted to be opened and closed to open and close said pipe to the atmosphere, a gas collecting main, and a damper valve connecting said pipe and said 80 main and adapted to be closed when said cap is opened to open said ascension pipe to the atmosphere and to be opened when said cap is closed, of means for simultaneously operating said cap on said ascension pipe and said damper valve, said means including a fluid pressure operated cylinder, a piston in said cylinder connected to said damper valve, and link and lever mechanism connecting said piston with said cap. 90

4. The combination with a coke oven of the by-product type, having an ascension pipe through which the gaseous products may pass from the oven, a cap on the upper end of said pipe adapted to be opened and 95 closed to open and close said pipe to the atmosphere, a gas collecting main, and a damper valve connecting said pipe and said main and adapted to be closed when said cap is opened to open said ascension pipe to the atmosphere and to be opened when said cap is closed, of means for simultaneously operating said cap on said ascension pipe and said damper valve, said means including a fluid pressure operated cylinder, a piston 100 in said cylinder connected to said damper valve, and a link and rocker crank lever mechanism connecting said piston with said cap. 105

5. The combination with a battery of coke ovens of the by-product type, each of said ovens having an ascension pipe through 110 which gaseous products may pass from the oven, a cap on the upper end of each of said pipes adapted to be opened and closed to open and close said pipes to the atmosphere, a gas collecting main common to the ascension pipes of all of said ovens, and damper valves connecting said ascension pipes and said main and adapted to be closed when said ascension pipe caps are opened to open said ascension pipes to the atmosphere and 115 to be opened when said ascension pipe caps are closed, of individual means for operating the ascension pipe cap and damper valve on each of said ovens, said means comprising an individual fluid pressure operated cylinder mounted on each oven and operatively connected to the ascension pipe cap 120 and damper valve of said oven, a carriage 125

movable along said ovens, a source of fluid pressure on said carriage, means for detachably connecting said source of fluid pressure to the individual cylinders, and means operable from said carriage for controlling the flow of fluid pressure to said cylinders.

6. The combination with a coke oven of the by-product type, having an ascension pipe through which the gaseous products may pass from the oven, a cap on the upper end of said pipe adapted to be opened and closed to open and close said pipe to the atmosphere, a gas collecting main, and a damper valve connecting said pipe and said main and adapted to be closed when said cap is opened to open said ascension pipe to the atmosphere and to be opened when said cap is closed, of power operated means for operating said ascension pipe cap and damper valve, a source of power, means for detachably connecting said source of power to said power operated means, and means operable from a point remote from said cap and said damper valve for controlling the flow of power to said power operated means.

7. The combination with a battery of coke ovens of the by-product type, each of said ovens having an ascension pipe through which gaseous products may pass from the oven, a cap on the upper end of each of said pipes adapted to be opened and closed to open and close said pipes to the atmosphere, a gas collecting main common to the ascension pipes of all of said ovens, and damper valves connecting said ascension pipes and said main and adapted to be closed when said ascension pipe caps are opened to open said ascension pipes to the atmosphere and to be opened when said ascension pipe caps are closed, of a carriage movable along said ovens, a source of fluid pressure carried by said carriage, individual fluid pressure operated means for simultaneously operating the ascension pipe cap and damper valve on each of said ovens, and fluid pressure operated means for detachably connecting said source of fluid pressure to any one of said first named fluid pressure operated means.

8. The combination with a battery of coke ovens of the by-product type, each of said ovens having an ascension pipe through which gaseous products may pass from the oven, a cap on the upper end of each of said pipes adapted to be opened and closed to open and close said pipes to the atmosphere, a gas collecting main common to the ascension pipes of all of said ovens, and damper valves connecting said ascension pipes and said main and adapted to be closed when said ascension pipe caps are opened to open said ascension pipes to the atmosphere and to be opened when said ascension pipe caps are closed, of individual means for operating the ascension pipe cap and

damper valve on each of said ovens, said means comprising an individual fluid pressure operated cylinder mounted on each oven and operatively connected to the ascension pipe cap and damper valve of said oven, said fluid pressure operated cylinders being operable from a point remote from said caps and said valves.

9. The combination with a coke oven of the by-product type, having an ascension pipe through which the gaseous products may pass from the oven, a cap on the upper end of said pipe adapted to be opened and closed to open and close said pipe to the atmosphere, a gas collecting main, and a damper valve connecting said pipe and said main and adapted to be closed when said cap is opened to open said ascension pipe to the atmosphere and to be opened when said cap is closed, of fluid pressure means for simultaneously operating said cap on said ascension pipe and said damper valve, said fluid pressure means being operable from a point remote from said cap and said valve.

10. The combination with a coke oven of the by-product type having an ascension pipe through which the gaseous products may pass from the oven, a cap on the upper end of said pipe adapted to be opened and closed to open and close said pipe to the atmosphere, a gas collecting main, and a damper valve connecting said pipe and said main and adapted to be closed when said cap is opened to open said ascension pipe to the atmosphere and to be opened when said cap is closed, of fluid pressure operated means for simultaneously operating said cap on said ascension pipe and said damper valve, a source of fluid pressure adapted to be detachably connected to said means, and a valve mechanism for controlling the fluid pressure supplied to said means.

11. The combination with a battery of coke ovens of the by-product type, each of the ovens of said battery having an ascension pipe through which the gaseous products may pass from the oven, a cap on the upper end of said pipe adapted to be opened and closed to open and close said pipe to the atmosphere, a gas collecting main extending along said battery of ovens, and a damper valve connecting each of said ascension pipes with said gas collecting main, of an individual fluid pressure operated means for operating the ascension pipe cap and damper valve of each of said ovens, a source of fluid pressure adapted to be moved along said ovens, and means for detachably connecting said source of fluid pressure to said fluid operated means.

12. The combination with a battery of coke ovens of the by-product type, each of the ovens of said battery having an ascension pipe through which the gaseous products may pass from the oven, a cap on the upper

end of said pipe adapted to be opened and closed to open and close said pipe to the atmosphere, a gas collecting main extending along said battery of ovens, and a damper valve connecting each of said ascension pipes with said gas collecting main, of a fluid pressure cylinder mounted on each of said ovens and operatively connected to the ascension pipe cap and damper valve of the respective ovens, a carriage movable along said battery of ovens, a source of fluid pressure on said carriage, and means for detachably connecting said source of fluid pressure to any of said cylinders.

13. In an apparatus for operating an ascension pipe cap and damper valve of a by-product coke oven, the combination with a

fluid pressure operated cylinder, of a source of fluid pressure, and means for detachably connecting said source of fluid pressure to said fluid pressure operated cylinder, said means comprising a cylinder, a hollow piston in said cylinder and movable longitudinally relative thereto, a conical receiving head connected to said fluid pressure operated cylinder, and means carried by said piston adapted to form a sealed connection with said conical receiving head.

In testimony whereof we have hereunto set our hands.

HOWARD T. BENNETT.
JAMES McINTOSH.
THOMAS M. MCNELLY,
